Fig-7

FIG. 1 is a top right front perspective view of a pallet component showing my new design;

FIG. 2 is a top plan view thereof;

FIG. 3 is a left side elevational view thereof which is identical to the right side view shown in FIG. 1;

FIG. 4 is a bottom plan view thereof;

FIG. 5 is a front elevational view thereof;

FIG. 6 is a rear elevational view thereof;

FIG. 7 is a cross-sectional view thereof taken along line 7—7 of FIG. 3.

I claim:

The ornamental design for a pallet component, as shown.
